GUN MOUNT

Walter H. D'Ardenne, Jenkintown Manor, William J. Meinel, Huntingdon Valley, Weber de Vore, Horsham Township, Montgomery County, Robert W. Wolf, Philadelphia, Pa., assignors to Heintz Manufacturing Company, a corporation of Pennsylvania

Application November 14, 1942, Serial No. 465,616

10 Claims. (Cl. 89—37)

1

This invention relates to mounts for machine guns, automatic light cannon and similar armament.

The exigencies of the present war have presented a demand for mounts for machine guns and other comparatively light armament, which mounts, while shielded, may be maneuvered manually over a considerable range within a very limited operating radius, and without power assistance. A highly desired characteristic of mounts of this type is that they be simply designed as to be capable of quick and easy manufacture, with relatively few critical materials and with a minimum of machining operations. It is the principal object of the invention to provide mounts possessing such advantages.

Another object of the present invention is to provide an armor shielded mount which may be easily trained manually through 360° in traverse, and elevated from minus 10 degrees to plus 80 degrees by body movements of the gunner, and which a gunner of average height can sight with ease at any elevation without the use of steps or platform.

Another object of the invention is to provide a gun mount for machine guns and the like wherein a shield is mounted to move in train and elevation with the gun and in which the shield carries means extending rearwardly thereof and engaging the shoulders of the gunner so that the gun is pointed entirely by body movements of the gunner.

A further object of the invention is to provide a gun mount of the type referred to in the preceding paragraph in which equilibrating means are provided for partially equilibrating the weight of the shield and gun so as to facilitate operation of the mount by the gunner.

Still another object is to provide a mount as referred to in the two preceding paragraphs in which the shield is mounted so as always to be disposed between the gunner and the target under fire.

A still further object of the invention relates to the provision of a mount, which with a few simple operations and a single substituted part can be adapted at the battle front for machine guns and light automatic cannon of different types and calibers.

Another object is to provide a novel split ring and groove arrangement cooperating with the bearing assembly which supports a rotatable part of the mount.

An important feature of the invention resides in the provision of a mount, the parts of which

2

are so designed and disposed as to effect a well-balanced weapon while still permitting manipulation without power or power assistance within an operating radius smaller than heretofore possible in an armored mount.

The invention provides a shielded mount for both single and twin machine guns and the like.

These and many other objects of the invention will become more apparent from the following description and claims when read in conjunction with the accompanying drawings in which:

Fig. 1 is a side elevation of one embodiment of the invention shown as adapted for a single machine gun, normal, depressed and elevated positions of the gun being indicated in broken lines.

Fig. 2 is a rear plan view of the same embodiment of Fig. 1.

Fig. 3 is a top plan view of the same embodiment.

Fig. 4 is a side elevation of the base, pedestal tube, showing in dotted lines the equilibrator spring and the means joining it to the connecting rod.

Fig. 5 is a horizontal plan view taken on the line 5—5 of Fig. 4.

Fig. 6 is a detail sectional view of the upper portion of the structure shown in Fig. 4.

Figs. 7, 8 and 9 are respectively side, end and top elevations of a cast carriage employed for supporting the gun cradle, and shield and parts carried thereby on the pedestal and base.

Fig. 10 is a side elevation of the binder shaft used in locking the single gun mount.

Fig. 11 is a sectional view of the cover plate for the carriage.

Fig. 12 is a sectional view taken on the line 12—12 of Fig. 11.

Fig. 13 is a front view of the shield used in the single mount embodiment.

Fig. 14 is a side elevation similar to Fig. 1 but showing an embodiment of a mount for twin machine guns.

Fig. 15 is a rear elevation of the mount for twin guns shown in Fig. 14.

Fig. 16 is a top plan view of the modification of Figs. 14 and 15.

Fig. 17 is a top plan view of the carriage employed in the modification of Figs. 14 and 16.

Fig. 18 is a front elevation of the same structure.

Fig. 19 is a side elevation of the same structure.

Fig. 20 is an enlarged detail, of a portion of Fig. 19 partially broken away.

Fig. 21 is a view of the locking binder shaft used with the twin gun mount.

Fig. 22 is a view of the same shaft turned 90°.

Considering first the embodiment of the invention illustrated in Figs. 1 to 13, inclusive, the mount is comprised generally of a pedestal support base A, a carriage B, and a cradle C pivotally supported by the carriage. The cradle carries an armor plate shield D, provided with a sight opening and openings for the gun E supported by the cradle.

The upper part of the armor shield D carries adjustable shoulder braces generally indicated by the reference character F. Suspended from the cradle C is an adjustable seat strap G. In this embodiment, the front and rear sights H and H' respectively are supported directly on the gun E.

For purposes of illustration, the mount is shown as used with caliber .50 water-cooled machine gun of the Browning type, but as will be later apparent, the mount with a few adjustments and substitution of parts can readily be used with guns of other types.

The pedestal support.—The pedestal support A is comprised of a base plate 2 which is circular in form, and which for example, may advantageously be constructed of mild plate steel. The base plate 2 supports a central upright pedestal tube 4 which is secured to the base plate 2 by welding and by the strengthening ribs 6 welded to both tube and base plate. To render the base plate and ribs as light in weight as feasible, holes 8 and 10, respectively, may be cut in these parts. The base plate 2 is provided also with holes 12 to permit the mount to be bolted to the deck of a ship or other support. Although the top of the pedestal tube is covered against the weather, as will be described hereinafter, drain holes 14, 14' are provided at the base of the tube as well as in the center of the base plate. The pedestal tube 4 houses a powerful coil spring 16 (see Fig. 4) which acts as an equilibrator as will be described.

The equilibrator spring 16 at its lower end bears against the upper surface of the base plate 2 and at its upper end engages a two-piece block clamp 18 (Fig. 6), the lower piece 20 of which has a downwardly projecting tubular portion 22 of a diameter slightly less than the inner diameter of the coil spring 16. The two pieces of the block clamp 18 are provided with complementary semi-spherical cut outs 24 and 26 so as to form a socket for the ball end 28 of a connecting rod 30 when the two pieces of the clamp block are secured together by the bolts 32.

The carriage.—Supported on the pedestal tube 4 is the carriage B which advantageously is a one piece, high strength casting. This casting is provided with a central vertical bore of a diameter sufficient to permit the carriage to slide downwardly on to the top portion of the pedestal tube 4 and to be capable of rotating thereon.

As seen from the enlarged detail views of the carriage (Figs. 7, 8 and 9) the carriage is provided with a lateral upstanding arm 34, the upper end of which is provided with a transverse bearing opening 36 through which a pivot pin 38 (Fig. 1), carried by the cradle C, passes to provide a pivot point for the cradle and the parts carried thereby.

The carriage also is provided with an integral lug 40 having a threaded bore for receiving an adjustable stop member 42 which may be locked in adjusted position by the lock nut 44. The purpose of this stop will be explained later.

The body of the carriage is also provided with a

transverse bore 46 in which is disposed a binder shaft 48 adapted to be actuated by the locking handle 50 in a manner to be described.

The top of the carriage is covered by a plate 52 assembly comprising a plate 52, bolted as at 54 to the top rim of the carriage, and a sliding plate 56. Plate 52 is provided with a transverse rectangular opening, the edges 58 of which are flanged, as shown in Figs. 11 and 12, to engage complementary formed edges 60 on the sliding plate 56. The sliding plate 56 is thus adapted to move with a reciprocating movement across the top of the cover plate 52. As noted from Fig. 9, the sliding plate 56 is provided with a central opening 62 for the connecting rod 30.

The arm 34 of the carriage (Fig. 7) also carries a shipping lock arm 64, pivoted at one end and notched at the other, and which, as will be described, may be removed after the mount is assembled in battle position.

The base of the carriage B is provided at its lower end with an integral stepped flange, the upper portion 66 of which has threaded openings in its under surface to receive bolts 68 used in securing the carriage on the pedestal tube 4.

Fig. 4 illustrates the carriage B as assembled on the pedestal tube. This assembling is accomplished in the following manner. Referring to Fig. 6 it will be noted that the upper part of the pedestal tube has a ball bearing housing ring 70 secured thereto. The securing is effected by employing a retainer ring 72 (similar to a piston ring). The housing ring 70 has an annular cut-away portion which, with the outer wall of the pedestal tube, forms an annular groove 74, in which ball bearing races and balls 76 are disposed. These are held in place by an upper retainer ring 78.

The housing 70 is provided with vertical threaded holes 80 adjacent its outer periphery. When the carriage B is slid downwardly over the top of the pedestal tube 4, it will come to rest on the housing 70. The lower portion 82 of the stepped flange on the carriage will engage the ball races 76, while the upper portion 66 of the stepped flange will engage the housing 70 directly so that the carriage may be securely joined to the housing by passing the bolts 68 upwardly through the openings 80 in the housing and turning them tightly in the stepped flange on the carriage.

The cradle.—The cradle C employed may generally be of the type described and illustrated in the patent to Frederick T. Moore, No. 1,708,232. It consists of two outer parallel plates 84 and 86. These plates are secured in spaced relation by spacer tubes and bolts, such as those indicated by the reference numeral 88. The outer plates 84 and 86 are generally rectangular in shape with the rear portion having a downwardly projecting portion, the edge 92 of which is arcuate with respect to a center point coincident with the pivot pin 38. The pivot pin 38 passes through both of these plates and through the opening 36 in the arm 34 of the carriage B and thus furnishes the means for pivotally supporting the cradle and the structure carried thereby on the carriage.

The cradle further includes two inner parallel plates 96 and 98 which in this instance are rigid with the outer parallel cradle plates. The inner plates 96 and 98 are held in spaced relationship by bolts and spacers 97, some of which, such as 99, pass through the outer plates as well to secure the inner and outer plates rigidly together.

These inner plates each have a corresponding

upward projection 100 having aligned openings 102. The gun has a portion provided with a transverse hole which portion is adapted to be disposed between said projections 100 so that a removable securing pin (not shown) may be passed through the openings 102 and the hole in the gun to secure the gun in place. At the other end of the inner plates 96 and 98 another pin opening 104 is similarly employed to secure the gun to these inner plates by a pin.

The outer plates of the cradle have a spent cartridge case deflector 106 secured to their forward ends. The cradle at its other end supports the removable strap seat support G by means of the chains 108 hooked to the spool nuts 110 on the outer ends of the rear spacer tube and bolt 88 (see Fig. 2). The cradle C also supports and carries the armor plate shield D. This shield is generally of the shape shown in Figs. 1, 2, 3 and 13. It is secured to the outer cradle plates 84 and 86 by means of the bolts 112 which join it to angle pieces 114 welded or otherwise rigid with the outer cradle plates.

The shield D is provided with an opening 116 for the passage of the gun, and also large enough to permit the operator to engage the charging knob of the gun forwardly of the shield. This latter part of the opening is protected from the front by a forwardly projecting armor plate hand protector 118 welded to the shield proper.

Still further, the shield D is provided with two rearwardly projecting members 120 which, through the medium of the two-piece clamps 122, adjustably support the shoulder braces F.

Finally, the shield D at its lower inner surface has a sight ring case 124 secured thereto for housing the front sight ring H when the mount is transported or stored.

The cradle and the shield should be considered as one sub-assembly.

As seen in the top plan view (Fig. 3), a trunnion block 126 is secured between the outer side plates 84, 86 of the cradle. This trunnion block is provided with a threaded opening 128 to receive the upper threaded end of the connecting rod 30 (Fig. 4). The threaded end of the connecting rod, when the mount is assembled, extends upwardly into the threaded opening 128 in the trunnion block 126 after which the jam nut 130 is turned until it abuts the under surface of the trunnion block.

From the description given it should now be manifest that the cradle C, shield D and gun E, are all supported by the pedestal A through the carriage B, and that movement of the cradle, shield and gun in elevation (as indicated in the upper broken lines in Fig. 1) occurs about the pivot point 38 when the operator, with his shoulders in the shoulder braces F, raises or lowers his body.

It will be apparent that movement of the gun and shield in elevation and train is accomplished substantially entirely by body movements of the gunner transmitted by the shoulder braces to the parts of the mount which move in train and elevation.

It should also be apparent that as downward movement occurs, a considerable portion of the weight of cradle, shield and gun is absorbed by the compression spring 16, which, as described, is connected through the connecting rod 30 to the cradle.

Movement in elevation may be effected from minus 10° to plus 80°. Advantageously, the cradle may be provided with a small stop block 132

welded or otherwise secured to the outer cradle plate 86 adjacent its lower edge. This stop block 132 strikes the adjustable stop 42 on the carriage thus limiting downward movement to minus 10° and preventing damage to cradle parts which otherwise would strike the carriage.

In describing the carriage B, reference has been made to a shipping lock 64. This shipping lock, when the mount is shipped, is in the position shown in Fig. 2 in which its free notched end engages the spacer tube 88, which holds the outer side plates of cradle in spaced relationship at the rear. Naturally, before operating, this shipping lock must be removed by tilting the cradle, shield and gun upwardly about the pivot pin 38 until the notched end of the shipping lock 64 is disengaged and drops by gravity to the position shown in Fig. 7. During operation of the mount it is best to remove the shipping lock 64 entirely, which is easily accomplished by merely removing the bolt 134 (see Fig. 7).

While in transit, as well as during operation, the mount may be locked in any of its positions, both in elevation and in traverse by operating the locking handle. Locking in any position of elevation is accomplished by the clamping member 136 mounted loosely at the end of the binder shaft 48 inwardly of the locking handle 50, and which, when the handle is turned in one direction clamps against the outside surface of the cradle plate 86 adjacent the arcuate lower edge 92 (see Fig. 1).

The cradle, shield and gun, as indicated, are capable of rotary movement in traverse over 360° by reason of the mounting of the carriage on the ball races 76 near the upper end of the pedestal. Locking in any position in traverse, is likewise accomplished by manually turning the locking handle 50. The handle 50 is threaded on the end 40 of the binder shaft 48. The binder shaft 48 passes tangentially through the carriage B with one end loosely engaged in a recess in the inner wall of the carriage and the threaded handle end extending through an opening in the wall of the carriage B. As will be seen from Fig. 10, the binder shaft 48 is a round rod, the central portion of which is provided with an arcuate cut-out 138 which fits around the upper circumferential surface of the pedestal tube 4 when the carriage B is mounted on the pedestal tube. By turning the locking handle 50 the binder shaft 48 is caused to move lengthwise so that a portion of the surface of the arcuate cut-out engages and binds the pedestal tube. The more the locking handle is turned the greater is the binding action and the more effective is the locking.

In this modification of the invention the front and rear gun sights H and H' respectively, are carried directly by the gun through the medium of brackets. The front sight H is mounted on a bracket 121 which clamps around the water-cooled barrel of the gun E, while the rear sight H' is supported on bracket 123 which may be removably bolted to the upper surface of the gun at the rear.

From Figs. 2 and 3 it will be seen that the line of the gun sights is disposed in a slightly offset lateral direction with respect to the longitudinal axis of the gun. An offset sight opening 140 is also provided in the armor plate shield.

The outer side plate 84 of the cradle C, forwardly of the shield D (see Fig. 3), is provided with a bracket 142 to receive an ammunition chest (not shown).

It is one of the desirable features of this mount

that it can be installed and operated in a greatly reduced base surface space. For example, on certain types of ships only a very limited deck space is available for additional armament for anti-aircraft purposes and the problem is particularly acute with shielded mounts. The present mount admirably solves this problem.

To meet these requirements, the cradle, shield and gun are disposed forwardly a much greater distance than heretofore believed feasible. This obviously throws the trunnion point farther to the rear of the center of gravity of the gun, cradle and shield. Ease of operation with the present mount is effected, however, through the method of mounting the cradle, shield and gun, as described, including as it does the compression spring, and the connecting rod with ball and socket mounting. The compression spring 16 in the pedestal tube 4 and the connecting rod arrangement do not, it is true, effect a true balance of the mount in all positions, but because of the manner in which the spring is disposed and operates, the mount is effectively operated by having the man-effort applied in the most advantageous manner when the spring deficiencies occur either in elevation or depression.

The compression spring also cannot automatically compensate for the loss of weight of the expended ammunition. However, the equilibrium of the mount may be changed by adjusting the connecting rod with respect to the trunnion block 126, to the choosing of the individual gunner. In any event the change in manload at any point as far as expenditure of ammunition is concerned, need not be more than about 35 pounds, which in itself is not excessive.

The compression spring 16 is adjusted by merely loosening the jam nut 130 on the connecting rod 30, then turning the rod (in one direction to increase the spring load and in the other to decrease it), and finally tightening the jam nut again.

Reference has been made to a two-part cover for the carriage top, one part of the cover comprising a slidable member with an opening through which the connecting rod 30 extends. The sliding feature of the cover plate is necessary since upon elevation and depression of the cradle, shield and gun, the connecting rod transcribes a gyratory movement in one vertical plane.

Since movement of the mount when sighting is controlled by movement of the operator through the shoulder braces F, it is advantageous to have the braces adjustable to suit various operators. To this end the members 120 protruding rearwardly from the shield have round shank portions engaged by the upper halves of the two-piece clamp 122.

Mount for twin guns

A modified form of the invention as adapted for mounting twin machine guns and the like is illustrated in Figures 14 to 29 inclusive. This embodiment of the invention possesses many similarities to the embodiment just described. As in the first embodiment, the mount is comprised of a pedestal support A', a carriage B', a cradle assembly C' which supports twin machine guns E' and E'', an armor plate shield D', shoulder braces F' carried by the shield, an adjustable seat strap G', and front and rear sights H'' and H'''.

The pedestal support A', the shoulder braces F', and the adjustable seat strap G' may be identical with the pedestal support A, shoulder braces F, and seat strap G of the single gun mount embodiment previously described. However, in view

of the fact that the mount supports two machine guns E' and E'', it is obviously necessary to have a twin cradle structure C' differing from the single cradle structure C of the first embodiment, and,

5 furthermore, to support such a cradle structure, a carriage B', differing from the carriage B of the first embodiment, is required. Still further, the shield D' of the twin gun mount obviously possesses openings of different sizes and shapes than 10 the armor shield of the single mount. Finally, the sights on the twin gun mount instead of being mounted directly on the gun, as in the first embodiment, are in this instance mounted directly on the shield.

15 These differences in the twin mount, as compared to the single, will now be described in greater detail.

The twin carriage B'.—The carriage in the twin gun mount has a central body portion similar to

20 that of the carriage B in the single mount, but instead of one laterally upstanding arm such as 34 of the single mount, the twin carriage B' has two upstanding arms 202 and 204 provided respectively with transverse aligned openings 206 and 25 208' adapted to receive pivot or trunnion pins 208, 208' which pass through the cradle plates as will be described hereinafter. As in the single mount, the body portion has a projection 210 with an adjustable stop screw 212 which may be locked 30 in adjusted position by the locked nut 214.

As shown in Figures 17 and 18 particularly, the body of the carriage B' and the base of the upstanding arms 202 and 204 are provided with a transverse opening for a binder shaft 216 which 35 shaft performs the same function as the binder shaft 48 illustrated in Figure 10 in connection with the first embodiment. However, the binder shaft 216 is longer and has threaded portions at each end.

40 The binder shaft 216 is disposed within the transverse opening and extends from both ends. Clamping blocks 218 and 218' are disposed loosely over each end and at one end the bolts 220 and 222 are then placed in position. On the other end 45 a locking handle 224 is threaded on the binder shaft 216 and is prevented from coming off by a locking nut 226.

Differing further from the carriage B of the first modification, the carriage B' of the twin gun

50 mount embodiment has two spring cushioned shock absorbers 228 and 228' in the base of the arms 202 and 204. These shock absorbers are each provided with an inner integral shaft 230, the end of which is threaded. They are disposed 55 in recesses such as 232 (see Fig. 20). Springs such as 234 are disposed in the recesses 232 on the shaft portion 230. The threaded end of each shaft 230 extends inwardly to a transverse opening 236 so that a securing nut 238 may be threaded thereon.

60 When the mount is assembled in operation, the shock absorbers 228 take up the jarring caused by tilting of the mount rearwardly too far and thus prevent the cradle from injuring the carriage. A shipping lock 240 is provided which is

65 similar to, and serves the same purpose, as the shipping lock 64 of the first embodiment. In other respects the carriage B' is similar to the carriage B used with the single gun mount.

This description and illustration of the invention 70 has been given by way of example. It is manifest that changes may be made in the structure and arrangement of the parts without departing from the inventive concepts. Consequently, the invention is not limited except as 75 indicated in the claims which follow.

We claim:

1. A gun mount for machine guns and the like pointed entirely by body movements of the operator, comprising, a gun cradle, a support for said cradle, means for mounting said cradle on said support for rotary movement about a vertical axis and for pivoting movement in a vertical plane about a horizontal axis spaced rearwardly at all times from said vertical axis, means carried by said cradle for supporting a gun thereon intermediate of the gun but with the center of gravity of the gun disposed forwardly of said vertical axis, and equilibrating means disposed in said vertical axis and carried by said support and positively fixed to said cradle.

2. A gun mount for machine guns and the like pointed entirely by body movements of the operator, comprising, a vertical tubular support, a gun supporting member, means for mounting said member on said tubular support for rotary movement about the vertical axis of said support and for pivoting movement about a horizontal axis spaced rearwardly at all times from said vertical axis and in a vertical plane including said vertical axis, said gun supporting member when in horizontal position having means for supporting a gun intermediate of the gun but with the center of gravity of the gun normally disposed forwardly of said vertical axis and in said vertical plane, equilibrating means disposed within said tubular support and means threadedly connecting said equilibrating means and said gun supporting member, the latter at a point in said vertical plane forwardly of said horizontal axis.

3. A gun mount for machine guns and the like pointed entirely by body movements of the operator, comprising, a vertical tubular support, a gun supporting member, means for mounting said member on said tubular support for rotary movement about the vertical axis of said support and for pivoting movement about a horizontal axis spaced rearwardly at all times from said vertical axis and in a vertical plane including said vertical axis, said gun supporting member when in horizontal position having means for supporting a gun intermediate of the gun but with the center of gravity of the gun normally disposed forwardly of said vertical axis and in said vertical plane, a protective shield carried by said gun supporting member, the lower portion of said shield being disposed forwardly of said tubular support and the upper portion being disposed rearwardly of said tubular support, and equilibrating means disposed within said tubular support and threadedly fixed to said gun supporting member partially to equilibrate the weight of said shield and gun, the threaded fixation of said equilibrating means to said gun supporting member being at a point in said vertical plane forward of said horizontal axis.

4. A gun mount for machine guns and the like comprising, a vertical tubular support, a gun supporting member, means for mounting said member on said tubular support for rotary movement about the vertical axis of said support and for pivoting movement about a horizontal axis spaced rearwardly at all times from said vertical axis and in a vertical plane including said vertical axis, said gun supporting member when in horizontal position having means for supporting a gun intermediate of the gun but with the center of gravity of the gun normally disposed forwardly of said vertical axis and in said vertical plane, a protective shield carried by said gun supporting

member, the lower portion of said shield being disposed forwardly of said tubular support and the upper portion being disposed rearwardly of said tubular support, rearwardly extending gunner's shoulder braces carried by the upper portion of said protective shield and extending under the gunner's armpits and above his shoulders, said shoulder braces being constructed and arranged so that the mount is swung in traverse and moved in elevation solely through bodily movement of the gunner, and equilibrating means disposed within said tubular support and fixed to said gun supporting member partially to equilibrate the weight of said shield and gun, the point of fixation of said equilibrating means to said gun supporting member being at a point in said vertical plane forward of said horizontal axis.

5. A gun mount for machine guns and the like pointed entirely by body movements of the operator, comprising, a gun cradle, a support for said cradle, means for mounting said cradle on said support for rotary movement about a vertical axis and for pivoting movement in a vertical plane about a horizontal axis spaced rearwardly at all times from said vertical axis, means on said cradle for supporting a pair of guns intermediate their ends with their longitudinal axes spaced equidistantly from and parallel to said vertical plane and with the centers of gravity of said guns forwardly of said vertical axis, and equilibrating means carried by said support and fixedly connected to said cradle.

6. A gun mount for machine guns and the like pointed entirely by body movements of the gunner, comprising, a vertical support, means for mounting a gun intermediate its ends on said support for pivoting movement, a body protecting armor shield secured to said mounting means to swing with the gun in all its positions of pivoting movement, and pointing means mounted on and extending rearwardly of the shield and engaging the shoulders of the gunner, said pointing means being so constructed and arranged that body movements of the gunner effect pivoting movements of said shield and thereby of said mounting means.

7. A gun mount for machine guns and the like pointed entirely by body movements of the gunner, comprising, a vertical support, means for mounting at least one gun intermediate its ends on said support for pivoting movement in two directions at right angles to each other, a body protecting armor shield secured to said mounting means to swing with the gun in all positions of its pivoting movement so as to be disposed between the gunner and the target under fire, and means mounted on and extending rearwardly of the shield and engaged by body portions of the gunner and so constructed and arranged that body movements of the gunner effect pivoting movements of said shield and thereby of said mounting means.

8. A gun mount for machine guns and the like pointed entirely by body movements of the gunner, comprising, an upright pedestal support, a gun cradle mounted on said support for rotary movement in a horizontal plane and for pivoting movement in a vertical plane, means in said cradle for mounting a gun intermediate its ends, a body protecting armor shield secured rigidly with said cradle to swing with the gun in all its positions of pivoting movement so as to be disposed between the gunner and the target under fire, and means carried by the shield and extend-

ing rearwardly therefrom for engaging the shoulders of the gunner, said last mentioned means being so constructed and arranged that body movements of the gunner effect pivoting movements of said shield and thereby of the gun cradle and gun. 5

9. A gun mount for machine guns and the like pointed entirely by body movements of the operator, comprising a base support including an upright tubular member having circumferential grooves therein, a gun cradle, means for supporting said cradle on said tubular member for rotary movement thereabout and for vertical pivoting movement about a horizontal axis spaced rearwardly at all times from the longitudinal axis of said tubular member, said gun cradle having means for supporting a gun intermediate of its ends and with the center of gravity of the gun disposed forwardly of said horizontal axis, and equilibrating means carried by said tubular member and connected to said cradle at a point forwardly of said horizontal axis, said means for supporting said cradle on said tubular member comprising split rings disposed in said circumferential grooves in said tubular member, a bearing assembly supported by said rings, and a body having a cylindrical bore therethrough and rotatably supported on the upper end of said tubular member by said bearing assembly. 10

10. A gun mount for machine guns and the like pointed entirely by body movements of the operator, comprising a base support including an upright tubular member having circumferential grooves therein, a gun cradle, means for supporting said cradle on said tubular member for rotary movement thereabout and for vertical pivoting movement about a horizontal axis spaced rearwardly at all times from the longitudinal axis of said tubular member, said gun cradle having means for supporting a gun intermediate of its ends and with the center of gravity of the gun disposed forwardly of said horizontal axis, and equilibrating means carried by said tubular member and connected to said cradle at a point forwardly of said horizontal axis, said means for supporting said cradle on said tubular member comprising split rings disposed in said circumferential grooves in said tubular member, a bearing assembly supported by said rings, and a body having a cylindrical bore therethrough and rotatably supported on the upper end of said tubular member by said bearing assembly, said body hav- 15

ing an upstanding offset arm, and pivot means carried by said arm for supporting said cradle for said pivoting movement about said horizontal axis. 20
